UNITED STATES PATENT OFFICE.

ALFRED TENNYSON FLINT AND EDWIN FANSHAW, OF SHEFFIELD, ENGLAND.

GAME-BOARD.

No. 919,148.

Specification of Letters Patent.

Patented April 20, 1909.

Application filed May 8, 1908. Serial No. 431,584.

To all whom it may concern:

Be it known that we, ALFRED T. FLINT and EDWIN FANSHAW, subjects of the King of Great Britain and Ireland, residing at 5 Sheffield, in the county of York, England, have invented certain new and useful Improvements in Game-Boards, of which the following is a specification.

This invention relates to game-boards divided into squares and provided with movable playing-pieces; and it consists in the novel construction and combination of the parts hereinafter fully described and claimed.

15 In the drawings, Figure 1 is a perspective view of the game-board. Fig. 2 is a plan view of the game-board, from below. Figs. 3 and 4 are cross-sections, taken on the lines 1—2 and 3—4, respectively in Fig. 2.

20 The game-board consists of a hollow box or inverted trap A' having a flat top which is marked with a series of squares or sections on its surface. Certain of these squares are cut away to form holes B. In the example shown the board is divided into two 25 parts, one for each player, and these parts are separated by a bar or bridge A, and a row of holes B is arranged on each side of the bridge. Each hole is provided with a 30 trap-door C mounted on a pivot D and provided with a weight E, or any equivalent means, for normally holding it raised so as to close the hole pertaining to it.

The playing-pieces consist of disks a, 35 which are moved from one square to another by the players. When one of these pieces is moved onto a trap-door the weight of the piece causes the trap-door to descend automatically, so that the piece is discharged into the hollow box, and the trap-door then rises to its original position.

In order to vary the playing of the game the trap-doors are provided with movable locking-devices.

45 F is an endless band arranged between the two rows of trap-doors and which passes over rollers G journaled in bearings G¹ secured to the underside of the board. The shaft I of one of these rollers is provided 50 with a knob i, for revolving it, secured to its end portion outside the board. The endless band F is provided with lateral projections H at its side edges, at various points of its length. When any one of these projections 55 comes under the free end portion of a trap-

door it prevents the weight of the piece a from depressing the trap-door. The band F is moved from time to time to lock the different trap-doors, and in accordance with pre-established rules for playing the game. 60

The game is played in a similar manner to the well known game of "checkers", each player having a set of playing-pieces or men, distinguished by color or form, and the pieces being moved across the board 65 from opposite sides, and from one square to another in succession.

What we claim is:

1. A game-board having its surface divided into squares and provided with holes 70 corresponding to certain of the said squares, and having also depressible trap-doors pivoted on one side of the said holes and normally filling them flush with the surface of the board and adapted to tilt under the 75 weight of playing-pieces and permit the passage thereof through the holes, and having also means for closing the trap-doors automatically after the playing pieces have passed through the holes. 80

2. A game-board having its surface divided into squares and provided with holes corresponding to certain of the said squares, and having also in said holes depressible trap-doors filling the same and pivoted at 85 one edge and adapted to tilt under the weight of playing-pieces and permit the passage thereof through the holes, and having also locking-devices for securing certain of the said trap-doors. 90

3. A game-board having its surface divided into squares provided with holes corresponding to certain of the said squares and arranged in two rows, and having also in said holes depressible trap-doors filling 95 the same and pivoted at one edge and adapted to tilt under the weight of the playing-pieces and permit the passage thereof through the holes, and having also a band supported between the rows of holes 100 and provided with lateral projections for locking certain of the trap-doors, and means for moving the said band longitudinally.

In testimony whereof we affix our signatures in the presence of two witnesses.

ALFRED TENNYSON FLINT.
EDWIN FANSHAW.
